DESIGN.

I. J. BAXTER.

ORNAMENTATION OF SINKS.

No. 16,210.

Patented Aug. 25, 1885.

UNITED STATES PATENT OFFICE.

ISAAC JAY BAXTER, OF PEEKSKILL, NEW YORK.

DESIGN FOR THE ORNAMENTATION OF SINKS.

SPECIFICATION forming part of Design No. 16,210, dated August 25, 1885.

Application filed July 8, 1885. Term of patent 7 years.

To all whom it may concern:

Be it known that I, ISAAC JAY BAXTER, of Peekskill, in the county of Westchester and State of New York, have invented and produced a new and original Design for Sinks, of which the following is a full, clear, and exact description.

Reference is to be had to the accompanying photograph, which shows in perspective my newly-designed sink.

My design consists in the ornamentation of the body, back, and legs of the sink, as shown in the photograph.

The body A shows double inclines *a* *b*, offset from each other to show a ledge, *c*, between the inclines. The upper incline, *a*, is surmounted by a ledge, *d*, which shows double inclines *d* *d'* at its upper surface. The outer surface of the upper incline, *a*, is ornamented with scalloped festoons *e*, and the outer surface of the lower incline, *b*, is ornamented with the scalloped festoons *f*, and also with the points *g*, and parts of moline-crosses *h* on the points *g*. The points *g* are central to the festoons *f*. The corners of the body A are truncated, as at *i*. The legs B are hexagonal in cross-section, showing six panels, each of which is ornamented with festoons and points *k* *l* and crosses *m*. *n* *n* are circumferential ribs or members that join each other below the crosses *m*. At the center of each leg is the depression *o*, and below it the rib or member *p*, and at the bottom is the foot *q*, member *r* and depression *s* above, and depression *t* be-

low the member *r*. The back C is ornamented at its edge with a border rib, *u*, that shows two inclined surfaces, *u* *u'*, joining each other in a sharp edge. In each upper corner the back is ornamented with fan-shaped devices *v*, and in the center at its upper edge, within border *u*, are ornamental devices consisting of three festoons, *w* and *w'*. In the central festoon, *w*, is the point *x*, while in each side festoon, *w'*, is a part of a moline-cross, *y*. The front face of the back C is ornamented near each end with open-work soap-shelf projections *z*, and also with central vertical enlargements, *z'*, with vertical three-panel portion *z''*, and enlargement *z'''* above the three-panel portion *z''*, and upper corrugated half-globe or dome air-chamber, *z'''*. The enlargement *z'*, coming between the half-globe *z''* and the panel portion *z''*, gives the central enlargement, *z'*, a very symmetrical and handsome appearance. The edges of the back show points *a'* and intermediate depressions, *a''*, and in the center at its upper edge is the enlargement *a'''*, that surmounts the festoons *w* *w'* like a crown and gives the whole the appearance of a costly panel.

I claim—

The herein-described design for sinks, consisting in the ornamentation of the body, back, and legs of the same, as shown.

ISAAC JAY BAXTER.
